UNITED STATES PATENT OFFICE

JOHN NOWAKOWSKI, OF DETROIT, MICHIGAN

DESIGN FOR AN ORNAMENTAL SHIP

Application filed February 10, 1931. Serial No. 38,604. Term of patent 3½ years.

To all whom it may concern:

Be it known that I, JOHN NOWAKOWSKI, a citizen of the United States, residing at Detroit, in the county of Wayne and State of Michigan, have invented a new, original, and ornamental Design for an Ornamental Ship, of which the following is a specification, reference being had to the accompanying drawings, forming part thereof.

I claim:

The ornamental design for an ornamental ship as shown.

JOHN NOWAKOWSKI.
